LOADER OF THE DIPPER TYPE

George R. Dempster, Knoxville, Tenn.

Application May 13, 1947, Serial No. 747,689

4 Claims. (Cl. 214—131)

1

This invention relates to loaders of the dipper type, and more particularly to loaders that can be applied to trucks or tractors either as a front end loader or a rear end loader.

It is an object of this invention to provide an improved loader of the type characterized which may be readily operated by a fluid pressure system that can be mounted on the chassis of the vehicle as a self-contained unit and powered, if desired, from the engine of the vehicle.

Another object of this invention is to provide a loader of the type characterized with improved means to effect a crowding action of the dipper to assist in operating the same when resistance is encountered.

Another object of this invention is to provide an improved loader of the type characterized with means for facilitating a change in the angle at which the dipper is made to act.

Another object of this invention is to provide an improved loader of the type characterized wherein the emptying of the dipper is effected automatically by reason of the same being moved above a predetermined position.

Another object of this invention is to provide an improved loader of the type characterized which may take the form of an attachment that may be readily applied to known rigs for raising and lowering loads and also, preferably, for moving said loads forwardly and rearwardly with respect to the chassis of the vehicle on which the rig is disposed.

Another object of this invention is to provide an improved loader of the type characterized which may be readily conditioned for operation on upwardly or downwardly inclined surfaces and for digging below or above the level of the surface on which the vehicle is disposed.

Another object of this invention is to provide an improved loader of the type characterized which is so operated by fluid pressure as to effect a wide range of movement of the dipper and also provide flexibility of service.

Another object of this invention is to provide an improved loader of the type characterized which is of such construction that it may be readily applied to either trucks or to tractors, and which may be used either at the front or the rear end of the vehicle with which it is associated.

Another object of this invention is to provide an improved loader of the type characterized which when used as a front end loader is so constructed that it may be compactly associated with the engine of the vehicle when moving from place to place.

2

Another object of this invention is to provide an improved loader of the type characterized which is simple and rugged in construction, easy to operate, and highly efficient in use.

5 Other objects will appear as the description of the invention proceeds.

The invention is capable of receiving a variety of mechanical expressions, two of which are illustrated on the accompanying drawings, but it is desired to expressly understand that the drawings are for purposes of illustration only, and are not to be construed as a definition of the limits of the invention, reference being had to the appended claims for that purpose.

10 Referring in detail to the drawings, wherein the same reference characters are used to designate corresponding parts in the several figures,

Fig. 1 is a somewhat diagrammatic side elevation of a rig embodying the present invention used as a rear end loader on a truck;

15 Fig. 2 is a corresponding view of another embodiment of the present invention used as a front end loader on a tractor; and

Fig. 3 is a fragmentary bottom view of the dipper, to show the automatic latch employed on the dipper of both embodiments, as viewed from the line 3—3 of Fig. 1.

20 While the embodiment of Fig. 1 has been shown as a rear end loader and the embodiment of Fig. 2 as a front end loader, it is to be expressly understood that the former may be used as a front end loader and the latter as a rear end loader. Similarly, while Fig. 1 shows the embodiment there illustrated as mounted on a truck and Fig. 2 shows the embodiment there illustrated as mounted on a tractor, it is to be expressly understood that the former may be used on a tractor and the latter on a truck.

25 Referring first to Figs. 1 and 3, the present invention is shown as embodied in an attachment for transporting and dumping equipment of the general type shown, for example in Dempster Patent No. 2,179,779, granted November 14, 1939, for Transporting and Dumping Equipment, but it is to be expressly understood that if desired the rig now to be described may be furnished originally as a complete loading unit of the dipper type.

30 As here illustrated, the chassis 10 of a truck of any suitable character is provided with a horizontal frame 14 that may be secured to the chassis in any suitable way, as by bolts 9 and tie members 8, or the frame may be a part of the chassis. Frame 14 provides a pair of parallel channel-shaped tracks running lengthwise of the frame as in said Dempster patent, and a carriage

13 mounted on suitable rollers 12 may be moved forwardly and rearwardly on said tracks by a piston or plunger operating in a cylinder 11 carried by said frame and connected to the carriage 13 by a plunger or piston rod 15. Mounted on said carriage 13 is an upwardly extending frame member 16 of any suitable construction, said member acting as a skidway when the rig is used as a transporting and dumping rig, and being rendered suitably rigid by bracing 17 as well understood in the art. The rear end of the frame may be provided with an apron 18 to act as an abutment for the dipper to be described as well as for buckets and other loads when frame 16 is used as a skidway.

Pivotedly mounted at 20 on said frame 14, at the forward end thereof, is a boom 21 preferably composed of a pair of boom arms pivoted at the opposite sides of said frame and connected at their free ends by a rigid transverse member 20'. A second transverse connecting member 22 in the boom structure has pivotally attached thereto at 23 the rod 24 of a piston or plunger 25 working in a cylinder 26 which is pivoted at 27 to a transverse frame member 28 supported in any suitable way on frame 14. Suitable piping for conveying fluid under pressure to the cylinders 11 and 26 is shown at 29 and may be connected to any suitable pump and reservoir carried by the vehicle.

By introducing fluid of any suitable character, preferably oil, by means of a pump that may be powered from the engine of the vehicle, plunger 25 may be moved outwardly with respect to the cylinder 26, pivoting the boom from the full line position shown in Fig. 1 to the dotted line position; and when the end of the boom is provided with suitable hooks, chains or cables, any suitable bucket or other load may be moved thereby up the skidway 16, after which by operating the cylinder and piston mechanism 11, 15 the carriage 13, 16, may be moved forwardly with respect to the truck chassis; then by withdrawing fluid from the cylinder 26 the load may be deposited on the inclined frame members 19, all as well understood in the art. By reverse operation, the load may be picked up from the frame members 19 and moved to the rear of the chassis for deposit or dumping. The rig as so far described constitutes a transporting and dumping rig well known to the art and therefore it is not shown or described in greater detail.

While the loading provisions next to be described are preferably used with or incorporated in a rig of the type wherein the skidway may be moved forwardly and rearwardly with respect to the chassis by piston and cylinder mechanism 11, 15 for reasons to be explained, it is to be expressly understood that within the broader aspects of the present invention these provisions may be used with or incorporated in another well known type of rig of similar construction except that the upwardly extending member 16 is fastened rigidly in position at the rear of the frame 14 instead of being movable rearwardly and forwardly thereon.

According to the present invention when embodied in an attachment for rigs of the type above described means are provided whereby a dipper and actuating mechanism therefor may be readily added to the upwardly extending member 16 or skid frame and operated by the boom mechanism, and as readily removed so that by use of hooks, chains or cables the rig may be used at other times as a transporting and dumping

equipment, although if preferred the entire rig including the parts above described may be originally installed as a unit designed only as an operating mechanism for a dipper. As here shown, a dipper stick 30 is pivotally attached to member 16 at 31 and at 32 to the wall 42 of a dipper 33 of any suitable form, size and construction. While, if preferred, a single dipper stick 30 may be pivoted to the member 16 in the median transverse plane thereof, with a medial pivotal attachment to the dipper, the present invention preferably employs a pair of like dipper sticks 30 pivotally mounted at the sides of member 16 and on spaced lugs on the dipper wall 42. The pivotal mounting 31 may be of any suitable construction but when the dipper mechanism is provided as an attachment the pivots may conveniently take the form of readily insertable and removable bolts so as to facilitate the conversion of the rig from one to function as a transporting and dumping equipment to one to function as a dipper loading equipment.

Dipper 33 has the usual open side 60 and the side 54 which performs the digging function 25 is suitably reinforced and provided with a suitable beveled tongue or a plurality of beveled teeth 34 for biting into the material into which the dipper is to be forced. Pivotally attached to the sides of the dipper at 35 are rigid rods 36 which are pivoted at 37 to the free ends of the arms of the boom 21. Also pivotally attached at 38 on lugs on the wall 42 of said dipper are arms 39 that are pivotally attached to the dipper sticks at 40 so as to control the angular position of the dipper with respect to the dipper stick, and said arms 39 preferably have a plurality of apertures 41 so as to provide adjustment of the length of the arms 39 from the pivots 40 on the dipper sticks 30 to the pivots 38 on the dipper 33. Dipper 33 is also provided with a movable wall 43 at its side opposite the open side and which becomes a dump bottom when the dipper is moved to the dotted line position in Fig. 1. Said movable wall may be of any suitable construction and is here shown as provided with a pair of bars 44 (see Fig. 3) which are curved at 45 (Fig. 1) with the free ends of said curved portions 45 pivoted at 46 on lugs on the wall 42 of the dipper, the pivot axis being 50 so disposed that when the dipper is moved to its upper dumping position the wall 43 will move clear of the opening in the dipper, while when the dipper is restored to its digging position as shown in full lines in Fig. 1 the wall 43 will move back into dipper closing position where it will be automatically locked by the latch mechanism next to be described.

As shown in Fig. 3, wall 43 carries a rectilinearly movable latch bar 48 pivoted at 49 to a lever 50 that is pivoted at 51 on said wall 43. Latch bar 48 extends under one or more suitable guide members 52 and has its free end projecting through a suitable opening in a catch member 53 formed on or secured in any suitable way to the wall 54 of the dipper. Lever 50 is urged by a spring 55, attached at its opposite ends to the lever 50 and to the wall 43 of the dipper, so as to project the end of bar 48 into the opening in the member 53, and the end of said bar 48 is suitably beveled or curved so that when the movable wall 43 swings into closed position the latch bar 48 is cammed inwardly against the tension of the spring 55 until it is in alignment 75 with the opening in the member 53, whereupon

the spring 55 will draw the latch bar into its locking position.

Attached to the end 56 of the lever 50 is a suitable cord or cable 57 which extends upwardly and is attached at 58 to a point on the member 16 which is at a suitable distance below the pivot 31. Cable 57 preferably has at a suitable point in its length a turnbuckle 59 so that the length of said cable may be adjusted to function as next to be described. Owing to the fact that the cable 57 is attached to the member 16 at a point below the pivot 31, movement of the dipper stick 30 beyond an approximately horizontal position results in the distance between the point 58 and the point 56 on the dipper being increased so that, as the length of the cable 57 between said points 56 and 58 is substantially fixed, the lever 50 is pulled in a clockwise direction as viewed in Fig. 3 to withdraw the latch bar 48 out of the opening in member 53. Thereby the wall 43, which is now in approximately horizontal position as shown in dotted lines in Fig. 1, will swing around its pivot 46, discharging the contents of the dipper. When, however, the dipper is returned to the position shown in full lines in Fig. 1, cable 57 is slackened so that the latch bar 48 is free to be returned into locking engagement with the member 53 by spring 55 as heretofore described.

Whether the loading mechanism is supplied originally as a complete unit as shown in Fig. 1 or the dipper mechanism is provided as an attachment for a transporting and dumping equipment already in service, lowering of the boom 21 to the position shown in full lines in Fig. 1 disposes the dipper 33 in digging position. In this position the rods 36 extending from the free end of the boom 21 to the sides of the dipper press the dipper firmly into engagement with the surface at which the digging is to occur. Then by moving the boom 21 upwardly by means of the plunger 25 the dipper is made to swing through an arc, the lip or teeth 34 biting into the material to be loaded and forcing the same through the open side 60 into the dipper. Owing to the disposition of the cylinder 26 a powerful leverage is imposed on the dipper, and at the same time the dipper may be swung through a relatively large arc while the travel of the plunger 25 may be kept within conveniently short limits. When the dipper reaches the position shown in dotted lines in Fig. 1 the cable 57 automatically releases the movable wall 43 which, because of the character and location of its pivotal mounting, swings free to permit discharge of the content of the dipper. Release of pressure in the cylinder 26 will then cause the boom and dipper to return to the full line position shown in Fig. 1, the movable wall 43 being automatically locked in closed position when the dipper is returned to digging position as before explained. When, as preferred, the frame or skidway 16 is mounted for movement longitudinally of the truck chassis the mechanism described possesses the additional advantage that by admitting fluid pressure alternately to opposite sides of the plunger in cylinder 11 a crowding action may be imposed on the dipper, the latter being moved back and forth in a substantially horizontal direction to overcome resistance, loosen boulders or otherwise obtain the benefits of so called "crowding" as understood in the art.

Referring now to Fig. 2 wherein a loading mechanism embodying the present invention is

shown as mounted as a front end loader on a tractor, 62 designates any suitable frame mounted on the chassis of the tractor of any suitable character and construction, or it may be the chassis frame of the tractor. The end of the frame 62 is shown as provided with an apron 61. Mounted on frame 62 is suitable upright framing 63 braced at 64 and on which is pivoted at 65 a boom 66 preferably composed of a pair of side arms suitably connected at their free end by a transverse member 67 so that when in lowered position the boom may straddle the engine 68. The arms of boom 66 are also connected by a suitable rigid transverse member 69 to which is pivoted the fluid pressure mechanism for raising and lowering the same. While a single centrally arranged fluid pressure device may be used where space permits, the embodiment illustrated comprises a pair of cylinders 70 pivoted to the frame 62 at 71 and having plungers 72 which are pivotally connected at 73 to member 69 at or adjacent the sides of the boom.

In this embodiment an upstanding frame 75 is pivotally mounted at 76 on the end of the frame 62 and has pivotally mounted thereon at its upper end, as shown at 77, a generally L-shaped dipper stick 78 that is pivotally connected at 79 to any suitable dipper 80 which may be, and is illustrated as, of the same construction as in the embodiment of Fig. 1. In the form shown, the frame 75 is of generally rectangular construction and a pair of dipper sticks 78 are pivotally connected at the sides of the frame 75 and on spaced lugs on the dipper 80, but if preferred, a single dipper stick 78 may be disposed in the transverse medial plane of the dipper 80, in which event the frame 75 may be a centrally arranged upright lever or narrow frame member disposed in the transverse medial plane of the frame 62. As in the embodiment of Fig. 1 rigid rods or links 81, or it could be a centrally arranged rigid rod or link, are pivotally connected to the free end of the boom at 82 and to spaced lugs on the dipper at 83. A control arm or arms 84 are also pivoted on the dipper at 85 and to the dipper stick or sticks 78 at 86, arm or arms 84 being preferably provided with a plurality of apertures 87 for adjustment of the effective length of said arm or arms as explained in conjunction with the movement of Fig. 1. Frame 63, 64 also carries a suitable rigid transversely extending member 85 supported on suitable frame elements 86, and pivotally mounted on said member 85 at 87 are one or a pair of cylinders 88 whose plungers 89 are pivotally connected to the frame 75 at 90. A single cylinder and plunger 88 and 89 may be disposed in the medial transverse plane of the frame 62 but if it is desired that the fluid pressure mechanism clear the engine a pair of such devices are used, one at each side of the structure.

Dipper 80 has a movable wall 91 pivoted to the side of the dipper at 92 as in the embodiment of Fig. 1, and wall 91 is preferably provided with an automatic latch mechanism which may be of the same construction as shown in Fig. 3. As in the embodiment of Fig. 3, said latch mechanism is connected by a cord or cable 94 to the frame 75 at a point 95 which is suitably below the pivot 77 so that swinging of the dipper beyond a substantially horizontal position will effect the automatic release of the latch and the opening of

the wall 91 as heretofore described in conjunction with the embodiment of Fig. 1.

In operation, the dipper is manipulated from the boom 66 in the same manner as heretofore described with respect to the embodiment of Fig. 1, the dipper being automatically discharged as described in conjunction with that embodiment. In this embodiment, however, the crowding action is effected by the operation of the plunger or plungers 89 which may be actuated from any suitable source of fluid under pressure, also used in actuating plungers 12, to tilt the frame 75 around its pivot 76 and thereby effect forward and rearward motion of the dipper 80 to obtain the desired crowding action. This embodiment has the further advantage that by actuation of the plunger or plungers 89 the frame 75 may be disposed in a plurality of angular positions, moving the same toward the right from its vertical position as viewed in Fig. 2 for shoveling into material on a down grade, or moving to the left from its vertical position as viewed in this figure for shoveling on an up grade. Thereby the dipper can be made to dig into material which is below or above the surface on which the vehicle is disposed. The L-shaped form of the dipper stick or sticks 78 also has the advantage of tending to hold the dipper firmly against the apron 61, while the rod or rods 81 function to press the dipper downwardly onto the surface with which the dipper is to cooperate as heretofore explained with respect to the embodiment of Fig. 1.

It will therefore be perceived that by the present invention a loading mechanism has been provided which may be readily mounted on either a truck or a tractor and disposed thereon so as to operate either as a rear end loader or a front end loader. The loading mechanism may also be provided as a complete unit as manufactured, or, as in the case of the embodiment of Fig. 1, it may be provided as a conveniently operable attachment that may be supplied for use with transporting and dumping equipment either of the type wherein the skidway thereof is stationary or of the type wherein the skidway thereof is movable forwardly and rearwardly with respect to the axis of the vehicle.

By reason of the fluid-pressure operation of the boom directly connected to the dipper through the rod or rods at the free end of the boom, as well as through the dipper stick or sticks, the dipper may be firmly pressed into contact with the surface with which it is to cooperate and then swung through a relatively wide arc for deposit of the scoured-up material, the discharge of said material being automatically effected as soon as the dipper has reached a predetermined elevation, after which the movable wall of the dipper is automatically returned to and locked in closed position as soon as the dipper is returned to digging position. By adjustment of the pivotal connection of the dipper stick to the dipper by arm or arms 39 or 84 the desired angular relationship of the dipper to the dipper stick may be nicely predetermined, and by adjustment of the turnbuckle in the cable 51 or 94 the level at which automatic dumping is effected may likewise be exactly fixed. The loading attachment of the present invention is strong and rugged, readily manipulated, flexible in operation, simple in construction so that it is easy to fabricate and assemble, and highly efficient in performing its several functions.

While the embodiments of the present invention illustrated on the drawings have been de-

scribed with considerable particularity, it is to be expressly understood that the invention is not limited thereto, as the same is capable of receiving a variety of mechanical expressions as will now be apparent to those skilled in the art while changes may be made in the details of construction, arrangement, size, proportion, etc., of the component parts, parts may be substituted by equivalent parts, and certain features used without other features, without departing from the spirit of this invention. Reference is therefore to be had to the claims hereto appended for a definition of the invention.

What is claimed is:

1. In loading equipment of the character described, the combination of a frame, a boom having a pivotal mounting adjacent an end of said frame, fluid pressure operated mechanism for raising and lowering said boom, an upwardly extending member mounted on a fixed pivot adjacent the other end portion of said frame said pivot holding said member against lengthwise movement, power means for pivoting said upwardly extending member about said pivot, a dipper stick pivoted to the upper end portion of said member, a dipper connected to said dipper stick and rigid link means pivotally connecting said boom and said dipper for relative bodily movement of said dipper stick with respect to said boom.

2. In loading equipment of the character described, the combination of a frame, a boom on a pivot adjacent an end of said frame, fluid pressure operated mechanism for raising and lowering said boom, an upwardly extending member carried adjacent the other end portion of said frame on a fixed pivot, power means for pivoting said upwardly extending member about said second pivot, a dipper stick pivoted to the upper end portion of said member, a dipper connected to said dipper stick, and rigid link means pivotally connected to said dipper and to the free end of said boom, said last-named means comprising a rod pivotally connected to the free end of said boom and to said dipper and operable by said boom to press said dipper into engagement with the surface with which the dipper is to cooperate.

3. In loading equipment of the character described, the combination of a frame, a boom having a stationary pivotal mounting adjacent an end portion of said frame, fluid pressure operated mechanism for raising and lowering said boom, an upwardly extending member carried by a fixed pivot adjacent the other end portion of said frame power means for pivoting said upwardly extending member about said pivot, a dipper stick pivoted at one end to the upper end portion of said member, means for securing an implement to the other end of said dipper stick, and rigid link means pivotally connected to said boom for swinging said dipper stick in a vertical plane for relative bodily movement with respect to said boom.

4. In loading equipment of the character described, the combination of a frame, a boom having a stationary pivotal mounting adjacent an end of said frame and normally extending approximately horizontally and relatively parallel to said frame, fluid pressure operated mechanism for raising and lowering said boom, an upwardly extending member mounted on a fixed pivot adjacent the other end portion of said frame, said pivot holding said member against lengthwise movement, power means for pivoting said upwardly extending member on said sup-

port, a dipper stick pivoted to the upper end portion of said member, a dipper connected to said dipper stick and rigid link means pivotally connecting said boom and said dipper for relative bodily movement of said dipper stick with respect to said boom.
